UNITED STATES PATENT OFFICE.

HENRY E. PETERSON, OF SEATTLE, WASHINGTON.

BOX-PRESS.

1,270,201.

Specification of Letters Patent. Patented June 18, 1918.

Application filed August 20, 1917. Serial No. 187,248.

To all whom it may concern:

Be it known that I, HENRY E. PETERSON, a citizen of the United States, and resident of Seattle, county of King, and State of Washington, whose post-office address is 2922 3rd avenue west, have invented a new and useful Improvement in Box-Presses, of which the following is a specification.

This invention relates to improvements in box presses of the type employed for positioning and holding the tops on fruit boxes while they are being nailed and the object of this improvement is to provide a strong and simple press of this nature that will 10 exert a pressure throughout the entire length of the boards that form the top of the box while the top is being fastened on.

A further object is to provide yielding means for holding the end cleats and the 20 cover boards of the box in their proper position in the press frame preparatory to placing them on the box.

Still further objects are to provide yielding pivots for the press frame and to provide 25 suitable mechanism on the lower part of the frame for locking the press frame down on the top of a fruit box.

The invention consists in the novel construction adaptation and combination of 30 parts of a box press as will be more clearly hereinafter described and claimed.

In the accompanying drawings Figure 1 is a view in perspective of a box press embodying this invention as it may appear 35 when in use.

Fig. 2 is a view substantially in vertical mid section of the same in an inoperative position.

Fig. 3 is a view in perspective illustrating 40 the press frame.

Fig. 4 is a fragmentary sectional view illustrating one of the springs for holding the end cleats and cover boards for the boxes.

45 In the boxing of fruit and particularly apples it is customary to form the cover of two separate boards and to fill the boxes slightly above the level of the top and then to secure the covers tightly over the fruit.

50 The boards used for the cover are usually of thin material and are often bowed upwardly in the center by the pressure of the fruit, so that cleats must be placed across the ends of such boards and the nails driven through both the cleats and boards to hold 55 the cover on the box.

The press frame hereinafter described is provided with devices for engaging and holding the cover boards and cleats, and with two spring members that extend lengthwise centrally of the two boards that form the box cover and yieldingly hold such boards to prevent them from being broken by the fruit heaped above the center of the box when the ends of the cover boards are drawn down onto the top of the box for 60 nailing.

Referring to the drawings throughout which like reference numerals indicate like parts, the numeral 5 indicates a rectangular frame mounted on legs 6 and having an upright box-like structure 7 secured to the rear side thereof.

The box-like structure 7 is formed with a rearwardly inclined portion 8 on its front 75 side against which the press frame rests when not in use and has a receptacle on the top thereof that is divided into a larger central compartment 10 for cover boards and two smaller end compartments 11 for 80 end cleats.

The front portion of the rectangular frame 5 is provided with oppositely disposed L-shaped guides 12 for the reception of boxes 13 upon which covers are to be 85 placed.

14 is a stop against which the bottom of the box abuts when it is placed on the guides 12 and pushed back into the correct position for having a cover placed thereon. 90

The press frame comprises two transverse members 15 to which are fastened two longitudinally extending spring members 16 having angularly bent ends 17 to which are secured end cross bars 18.

The members 15 are pivoted as at 20 to two springs 21 that extend through slots 22 in the wall 8 and are rigidly secured to a fixed support 23.

The ends of the cross bars 18 are turned 100 inwardly as at 24 to form stops against which end cleats 25 may rest when the press frame is in an upright position.

26 are springs that co-act with studs 27 in holding the end cleats 25 and also co-act 105 with studs 28 and 28' in holding the cover boards 30 for the box.

When the press frame is in the raised position as shown in Fig. 2 the cleats 25 may be inserted between the springs 26 and studs 110 27 and the cover boards may then be placed on the cleats, the edges of the cover boards

resting against the studs 28, and 28', respectively, which serve as stops and positioning means and the ends of the cover boards being engaged and held by the springs 26.

- 5 The end bars 18 of the press frame are each pivotally connected at a medial point with rods 31 that extend downwardly on opposite sides of the frame 5 and are articulated with opposite ends, respectively, of a 10 cross bar 32 that is secured to a foot lever comprising two divergent members 33 that are pivotally connected with the rear legs 6.

The forward ends of the members 33 are secured together and provided with a foot 15 plate 34 by which they may be depressed into the operative position shown in Fig. 1.

- 35 is a support or brace that is pivoted between the member 33 and adapted to engage with an inclined stop member 36 to 20 lock the several parts in the position shown in Fig. 1.

The support 35 is normally held in a rearwardly inclined position against a stop 37 by a spring 38 as shown in Fig. 2.

- 25 40 is a bell crank shaped foot lever that is pivoted to the foot plate 34 and has one end connected by a spring 41 with the support 35 so that when the outer end of the lever 40 is pressed downward the force of 30 the spring 41 will overcome the force of the spring 38 and the support will be lifted into an upright position against the stop 36.

42 are springs that normally hold the lever members and associated parts in a raised 35 position.

- The various parts of the device will normally be held in the positions shown in Fig. 2 by the springs 42. When covers are to be put on, the box is placed on the supports 40 12 and the end cleats and cover boards are placed in the press frame. The operator then takes hold of the top of the press frame and pulls the same outwardly, thus lowering the foot lever a sufficient amount to enable 45 him to put his foot on the end of the bell crank lever 40, press it downwardly onto the foot plate 34 and then exerts sufficient pressure on the foot plate to draw the ends of cover boards securely down on the top of 50 the box when they may be nailed.

As the ends of the cover boards are drawn down the springs 16 yieldingly support the central part of such boards and prevent them from being broken and the springs 55 21 form yielding pivots for the press frame and permit such frame to adjust itself to fit the top of the box.

What I claim and desire to protect by Letters Patent, is—

- 60 1. A box press comprising a support having a shelf adapted to hold a box, a press frame secured to said support by yielding pivots, and means for exerting a downward pull on the opposite ends of said press frame 65 at substantially medial points.

2. A box press comprising a support having an upwardly extending rear portion and a shelf adapted to hold a box, springs rigidly secured at one end to said rear portion, a press frame articulated with the free ends 70 of said springs to form yielding pivots, and means for exerting a downward pull on the opposite ends of said press frame at substantially medial points whereby said press frame will automatically adjust itself to fit 75 the top of a box.

3. A press of the class described comprising a supporting frame having a shelf adapted to hold a box, a press frame secured by 80 yielding pivot means to said supporting frame at substantially the same elevation as the top of a box, said press frame comprising spring members that extend lengthwise of the cover boards of a box, and means for exerting a downward pull on the opposite 85 ends of said press frame.

4. A press of the class described comprising a rear upright portion and a shelf adapted to hold a box, of a press frame hinged to 90 said rear upright portion and adapted to be forcibly lowered onto the top of a box, said press frame comprising means for holding the cover boards and end cleats for the box cover, and resilient spring members extending lengthwise of said cover boards to exert 95 a yielding pressure throughout the entire length of the same.

5. A press of the class described comprising a support having a shelf adapted to hold a box, a press frame secured to said support 100 by yielding pivots said press frame having two longitudinally extending spring members that extend lengthwise of the cover boards of a box, and means for exerting a downward pull on the opposite ends of said 105 press frame at substantially medial points.

6. A press of the class described comprising a frame having an upright back portion and a shelf in front thereof, of guides for holding a box on said shelf portion, a foot 110 lever on the lower part of said frame, a press frame articulated by a flexible pivot with said upright back portion at substantially the same elevation as the top of a box that is supported on said guides, rods medially 115 articulated with the ends of said press frame and connected with said foot lever whereby a downward pull will be exerted on said press frame when said foot lever is depressed, and means for holding said foot 120 lever in a depressed position.

7. A press of the class described comprising a supporting frame having a shelf adapted to receive a fruit box, a foot lever on the bottom of said supporting frame, rods extending upwardly from said foot lever on opposite sides of said frame and a press frame hinged by a yielding joint to said supporting frame and connected to said rods whereby it may be turned from an upright 130

into a horizontal position, said press frame comprising longitudinally extending flat resilient members, cross bars on the ends of said members, springs associated with said 5 cross bars, and stop means on said frame and co-acting with said springs to hold box cover boards and end cleats.

8. A box press comprising a frame that forms a shelf, box supporting guides on said 10 shelf, an upright structure on the rear of said frame, flat spring members secured to said upright structure, a press frame comprising transverse members that are pivoted to the ends of said flat spring members to 15 form yielding pivots, longitudinally extending flexible members secured to said flat spring members, end bars secured to said flat spring members, cleat retaining studs in said spring members, cover board retaining 20 studs in said transverse members, springs co-acting with all of said studs to hold end cleats and cover boards, downwardly extending rods secured to said end bars, a foot lever connected with said rods 25 for exerting a pull thereon and means for

holding said foot lever in a depressed position.

9. A box press comprising a support having a shelf adapted to hold a box, a press 30 frame pivoted on said support and adapted to be lowered onto the top of a box, a foot lever pivoted on said support, rods articulated with the ends of said press frame and connected with said foot lever, means to normally raise said foot lever, a stop on said support, a brace arm pivoted on said foot lever and engageable with said stop to hold said foot lever in a depressed position, a spring to normally hold said brace arm out 35 of engagement with said stop, a bell crank lever on said foot lever and a spring connecting said bell crank lever with said brace arm, said last named spring being strong enough to overcome the force of said first 40 named spring and raise said brace arm when said bell crank lever is depressed.

Signed at Seattle, Washington this 14th day of August, 1917.

HENRY E. PETERSON.
